UNITED STATES PATENT OFFICE.

JOHN T. SLOCOMB, OF PROVIDENCE, RHODE ISLAND, ASSIGNOR TO ECONOMY COOKER COMPANY, OF EAST PROVIDENCE, RHODE ISLAND, A CORPORATION OF RHODE ISLAND.

STEAM-PRESSURE COOKER.

Application filed December 18, 1920. Serial No. 430,117.

To all whom it may concern:

Be it known that I, JOHN T. SLOCOMB, a citizen of the United States, residing at Providence, in the county of Providence and 5 State of Rhode Island, have invented certain new and useful Improvements in Steam-Pressure Cookers, of which the following is a specification.

My invention relates to cooking vessels in 10 which the steam is not allowed to escape at low temperature, otherwise known as pressure cookers. This invention is an improvement upon the construction set forth in United States Patent No. 1,111,810 issued to 15 me Sept. 29, 1914.

The essential objects of my invention are to furnish a means for relieving excessive steam pressure in the pressure cooker in such a manner as to insure instantaneous 20 and certain operation and avoid the delayed action incident to the use of special safety valves which stick after corrosion of the parts; to avoid the use of any independent safety valve and utilize the receptacle cover 25 for this purpose; to render the steam pressure releasing means adjustable to any desired or predetermined degree; to prevent scorching and any change or loss of ingredients in cooking, and to utilize the confined 30 heat to a maximum.

To the above and correlated ends my invention consists in such parts and in such combinations of parts as fall within the scope of the appended claims.

35 In the accompanying drawings which form a part of this specification,

Figure 1 is a side elevation, partially in central vertical section of my pressure cooker,

40 Figure 2, a bottom plan view thereof, Figure 3, a section on line 3—3 of Figure 1,

Figure 4, a side elevation of the socket sleeve, and

45 Figure 5, an enlarged fragmentary vertical central section of the cooker body and contents.

Like reference characters indicate like parts throughout the views.

50 In its present and preferred form of embodiment the outer vessel comprises a base 7, a cylindrical side 8, and retracted neck 9 at whose upper end the material is outwardly bent around a ring 11 forming a flat seat 12, and having its free edge 13 resting

against the neck. This construction forms a solid flat rectangular rim adapted to accommodate a cover. The bottom 7 of the outer vessel is provided with radially disposed inclined shoulders 15. Welded to opposite portions of the side wall are ears 17 carrying pintles 18 pivotally engaging the arm portion 19 of a resilient yoke or bail 20.

A sleeve 21 on the yoke has a threaded perforation 22 to receive a set screw 23 registerable in a notch 24 in the yoke. The sleeve has a depending lug 25, and adjacent the latter is provided with a conical hole or socket 26. The sleeve or bearing member 21 may be integral with the yoke.

A vessel cover 28 has an annular marginal shoulder terminating in a peripheral flange 30 resting on the rim of the vessel. The center of the cover has integral therewith a vertical hollow post 32 having an internal 75 thread 33 engaging an external thread 34 on a sleeve 35 whose internal thread 36 engages a thread 37 on a rod 38 which has a head 39 on its lower end. A set screw 40 in the post engages the sleeve 35 which controls the vertical position of the rod 38. The sleeve has diametrically oppositely disposed cavities 41 on its upper end to accommodate a bifurcated wrench or other turning tool. Above its threaded portion the rod has fast 85 thereto lateral arms 42; and above the arms the rod has a tapering end 43 adapted to seat in the socket 26 and engage the lug 25 which forms an abutment.

Adapted for insertion into the vessel 6 is 90 a second vessel 45 consisting of a bottom 46 adapted to rest on the ribs 15, and a tapering cylindrical side wall 47 having its upper portion 48 offset to form an annular internal shoulder 49. Its cover comprises a top 50 and side flange 51 provided with bayonet slots 52 adapted to receive pins 53 fast in the portion 48 of the vessel body. Fast to the top of this cover are loops 55 in which are pivoted the ends of a bail 56.

Nested in the last described vessel is a 100 third vessel or pail 58 comprising a bottom 59 and a tapering cylindrical side wall 60 having at opposite sides near its top pins 61 adapted to register in bayonet slots 62 in the flange 63 of a cover top 64. Loops 66 on the cover loosely receive the ends of a bail 67. The vessel 58 is much shorter than the vessel 45, and cover flange 63 is supported 105 on the shoulder 49.

The vessel 38 and the lower portion of the vessel 45 furnish separate receptacles for the articles to be cooked.

The inner vessels are introduced and removed from the outer vessel by means of their respective bails, and the inner vessels are everywhere spaced from the outer vessel to allow the liquid and steam free access to all parts thereof. The bayonet slot engagement makes each of the inner vessels including its cover portable as a single element, but enables disengagement of the cover when necessary. The contents of the inner receptacles remain intact and no part of the ingredients therein escape.

The cover 28 acts also as the valve for releasing the steam from confinement when the pressure has become excessive. The degree of pressure allowed to generate in the receptacle before escape of the steam from confinement may be increased or diminished by manually rotating the rod 38 through the arms 42 either upwardly or downwardly. Because of the resilient character of the yoke 20 there is an increased resistance of the latter against the cover as the rod is elevated, thus confining an increased number of pounds of steam. After the rod has been elevated the distance to insure a desired number of pounds of resistance the sleeve 35 is rotated spirally until its lower end abuts against the head 39 of the rod, and prevents any further vertical travel of the rod. The sleeve may be fixed in any desired position by means of the set screw 40.

I claim:—

1. In a steam pressure cooking apparatus, a receptacle, a cover on the receptacle, a resilient yoke on the receptacle, a bearing member on the yoke, a threaded post on the cover, a sleeve having threaded engagement with the post and provided with an internal thread, and a rod engaging the bearing member and provided with a thread loosely engaging the internal thread of said sleeve.

2. In a steam pressure cooking apparatus, a receptacle, a cover resting on the receptacle, a resilient yoke on the receptacle, a bearing member on the yoke, a threaded post on the cover, a sleeve having threaded engagement with the post and provided with a thread, a rod engageable with the bearing member provided with a thread engaging said thread of said sleeve, and a head on the rod below the sleeve.

3. In a steam pressure cooking apparatus, a receptacle, a cover on the receptacle, a resilient yoke on the receptacle, a bearing member on the yoke, a tubular internally threaded post on the cover, a sleeve having threaded engagement with the post and provided with an internal thread, a rod engageable at its upper end with the bearing member and provided with a thread loosely engaging the internal thread of said sleeve, a head on the lower end of the rod engageable with the sleeve, and a set screw in the post engaging the sleeve.

4. In a steam pressure cooking apparatus, a receptacle, a cover on the receptacle, a resilient yoke on the receptacle, a bearing member on the yoke, a post on the cover, a spirally rotatable sleeve mounted on the post and provided with an internal thread, a rod engageable with the bearing member provided with a thread engaging the internal thread, and lateral arms on the rod.

5. In a steam pressure cooking apparatus, a receptacle, a cover on the receptacle, a resilient yoke on the receptacle, a bearing member on the yoke provided with a socket, a post on the cover, a spirally rotatable sleeve mounted on the post and provided with an internal thread, and a rod registrable in the socket provided with a thread engaging the internal thread.

6. In a steam pressure cooking apparatus, a receptacle, a cover on the receptacle, a resilient yoke on the receptacle, a bearing member on the yoke provided with a socket, a lug on the bearing member adjacent the socket, a post on the cover, a vertically adjustable sleeve on the post provided with a thread, and a rod registrable in the socket in contact with the lug provided with a thread engaging the first thread.

7. In a steam pressure cooking apparatus, a receptacle, a cover therefor serving as a valve for releasing excessive steam, means embodying a resilient yoke and adjustable means between the yoke and cover for regulating the degree of pressure allowed to generate in the receptacle before its escape therefrom, and a rotatable member and locking means to limit the movement of said adjustable means.

In testimony whereof I have affixed my signature.

JOHN T. SLOCUMB.
